HOSIERY AND METHOD OF PRODUCTION

Ralph E. Prim, Rome, Ga., assignor to Rome
Hosiery Mills, Rome, Ga., a corporation of
Georgia

Application July 3, 1951, Serial No. 234,981

4 Claims. (Cl. 66—172)

1

This invention relates to hosiery and methods of production. More specifically, it is concerned with self-supporting seamless hosiery wherein elastic yarn is incorporated in the top portion so that the latter will bind upon the leg of the wearer and thereby hold the stocking in place without necessitating the aid of a separate garter.

One of the aims of my invention is to provide an improved stocking of the kind referred to in which the elastic yarn is embodied in accordion stitching in such a way as to form a smooth anti-ravel selvage edge, and to be interlaced in spaced subsequent courses with absence of step down floats between successive rounds.

Another object of my invention is to provide a simple method whereby hosiery with a top having the above attributes, can be economically produced by standard forms of circular knitting machines of the multiple feed type equipped with suitable needle selecting means.

How the foregoing and other important objects and advantages are realized in practice will appear from the following detailed description of the attached drawings, wherein: Fig. 1 shows a self-supporting half hose or sock with an elastic top conveniently embodying my invention.

Fig. 2 is a fragmentary view of the portion of the fabric of the sock top within the confines of the broken line rectangle II in Fig. 1.

Fig. 3 is a diagrammatic view in plan, of a circular knitting machine arranged for the production of my improved hosiery.

Figs. 4-6 are views like Fig. 3 showing how the yarn feeds are successively introduced at the start of the knitting.

Figs. 7 and 8 are linear developments of the needle and jack actuating cams showing how the inelastic and elastic yarns are fed to the needles during the knitting of different portions of the top of the sock.

Except for the formation of its top 5, the sock illustrated in Fig. 1 may be of the usual seamless construction, with its leg and instep portions 6 and 7 of plain fabric produced by rotary knitting, and its heel 8 and toe 9 fashioned by oscillatory knitting in the well known manner.

In accordance with my invention, several inelastic (in this instance two) yarns and a covered elastic yarn are employed in forming the top 5 as an accordion stitch fabric, these yarns being designated 10, 11 and 12 respectively in Figs. 2-8. In Fig. 2, the needle and sinker wales of the top fabric are indicated by the characters N, N' and S respectively. The starting course 13 of the top fabric is knitted from the inelastic yarn 10 with

2

regular loops n thereof in alternate needle wales N, and with elongated loops n' thereof in the intervening needle wales N'. As shown, the elastic yarn 12 extends continuously through all of the sinker wale loops s of the first course 13 to produce a non-ravel or selvage edge. The second course 14 of the top fabric is formed from the inelastic yarn 11 with regular or normal loops n² in alternate needle wales N only, and said loops connected by floats which extend crosswise behind the elongated loops n' of the inelastic yarn 10. The third course 15 of the top fabric is formed, like the first course, from the inelastic yarn 10, and the fourth course 16 like the second course, from the inelastic yarn 11, with the elastic yarn 12 interlaced between interconnecting elongated loops n' of the inelastic yarn 10. The fifth and sixth courses 17 and 18 respectively, are formed throughout by regular loops of the inelastic yarns 10 and 11 with the elastic yarn 12 interlaced between the regular loops of said yarns 10 and 11 in the wales N' at the regions of interconnection of said regular loops. The remaining courses of the top fabric are all formed like the courses 17 and 18. It will of course be understood that in the actual fabric, the elongated loops of the inelastic yarn 10 are more contracted than as diagrammatically shown in Fig. 2, and therefore tend to draw together the selvaged edge portion of the stocking top marginally. As the result, the loose ends of yarns 10, 11 and 12 are locked or anchored against pulling out when the fabric is stretched as the stocking is drawn over the foot of the wearer. This locking or anchoring of the loose yarn ends is especially effective by reason of the accordion stitch formation of the selvage from the two inelastic or foundation yarns 10 and 11. If a contractile selvage edge only is desired at the top of the stocking, the elastic yarn can be omitted from the knitting shortly after the completion of the first course 13. My improved method of knitting can be readily carried out in a so called "multiple feed" circular machine arranged as diagrammatically illustrated on Figs. 3-8 of the drawings, the same having a needle cylinder 20 which, except during fashioning of the stocking heel and toe, is continually rotated in the direction indicated by the arrows in said figures. At a station A is the usual master group of knitting cams which includes main stitch cam 21, an auxiliary main stitch cam 22, a center cam 23 and a guard cam 24. Disposed in quadrant relation to station A is a second knitting station B with a stitch cam 25 and an associated needle elevation cam 26.

At a station C, approximately one hundred and eighty degrees from the station B, is a needle depressing cam 27. For needle selecting purposes, the machine is further provided with a series of jacks 30, one beneath each alternate needle 31, as well as with cams 32 and 33 for actuating said jacks. Adjacent auxiliary stitch cam 22 is a special withdrawable depressing cam 35 which plays an important part in the knitting of the stocking top as do also the cam at 36 and the rise at 37, as will presently be seen.

One of the usual retractable multiple yarn feeding fingers designated 40 at the throat (Figs. 3 and 6) at station A of the machine, I employ to serve the inelastic yarn 11. At the second knitting station B, above cam 25, a retractable finger 41 is used to feed the inelastic yarn 10, and at station C above the region of depressing cam 27, I have provided a retractable finger 42 for feeding the elastic yarn 12. In Figs. 3-6, the alternate needles 31 are indicated by solid circles and in Figs. 7 and 8 by heavy lines so as to be readily distinguishable from the intervening needles 31a.

The method of producing the sock of Fig. 1 in accordance with my invention is as follows:

With the cylinder 20 rotating counterclockwise as indicated by the arrow in Fig. 3, and with the needles all bare, the elastic yarn feed 42 is the first to be introduced. As the needles approach station C, the alternate ones 31 are elevated, as shown in Fig. 7, by action of the cam 32 upon the associated jacks 30 to receive the elastic yarn 12 within their hooks, after which they are lowered to a level slightly above the tuck level by cam 27, while the intermediate jack-less needles 31 pass at the tuck level and miss said yarn. A little further along in the direction of cylinder rotation, all of the needles are elevated somewhat by cam 36 with the result that the intermediate needles 31a pass up to the front of the elastic yarn 10 as exaggeratedly shown in Fig. 3. When the needle 31a of the intermediate series immediately in advance of the leading needle L 31 of the alternate series 31 approaches station B, the finger 41 is introduced as shown in Fig. 4. At station B all of the needles are raised to the latch clearing level by cam 26 as in Fig. 7, to take the inelastic yarn 10 and then knit the same as they are lowered to the stitch drawing level by cam 25. Thus, at station B, loops of the inelastic yarn 10 are drawn by adjacent needles to opposite sides of the elastic yarn 12 to form the accordion stitch non-ravel or selvage edge referred to hereinbefore in connection with Fig. 2. After passing under stitch cam 25, the alternate needles 31 are elevated to latch clearing level by the action of cam 33 upon the associated jacks 30 so that their butts will subsequently overtravel cam 35. At the same time, the intermediate needles 31a are elevated to the tuck level as they ride up cam 31, but after passing over the hump of the latter they are diverted downwardly by cam 35 to undertravel auxiliary stitch cam 22 of the main cam group as shown in Fig. 7, while the alternate needles 31 overtravel said cam 22. As needle L 31 approaches station A, the finger 40 is introduced as in Fig. 5 to feed the inelastic yarn 11 to the alternate needles 31 which, after underpassing center cam 23, are drawn down by stitch cam 21 to knit said yarn. Since, in traversing station A, the intermediate needles 31a are maintained at the stitch holding level by guard cam 24, they fail to take the inelastic yarn 11, but retain the loops of the inelastic yarn 10 previously

formed on them at station B. As the intermediate needles 31a are elevated slightly together with the alternate needles 31 by the cam rise at 34, they pass up to the front of the floats connecting the loops n^2 of the second course of the knitting (Fig. 2) formed upon the latter needles at station A. After completion of somewhat more than a single rotation of needle cylinder 20 to form the accordion stitch selvage, cam 35 is withdrawn from action, with the result that after having undertraveled cam 25 and moved up on the rise 37, all of the needles will be at the latch clearing level as in Fig. 8. As they continue on, all of the needles overtravel auxiliary stitch cam 22 to receive the inelastic yarn 11 at station A, and finally knit said yarn as they are drawn down to the stitch forming level by cams 23 and 21 at station A. During the second revolution of the cylinder, the elastic yarn 12 will again be taken by alternate needles as before at station C, and inelastic yarn 10 will be knitted at station B by alternate needles but, due to retraction of cam 35 upon completion of the selvage edge, fabric loops will thereafter be formed from the inelastic yarns 10 and 11 on all of the needles at stations B and A to produce two feed fabric with the elastic yarn interlaced between interconnecting plain loops of said inelastic yarns in adjacent courses.

The alternate long loops of yarn 10 in the selvage edge portion of Fig. 2 are occasioned by failure of the intervening needles 31a to knit at station A in Fig. 7, and the floats of the yarn 11 through knitting of said yarn by the alternate needles alone at said station. By employing two inelastic yarns and using two knitting stations in the machine as herein exemplified, it will be seen that the rounds of the elastic yarn 12 will be spaced by two courses throughout the stocking top 5.

After an elastic top of the desired length has been formed, the elastic yarn feed 42 may be retracted and the stocking leg and instep produced as a two feed fabric from the inelastic yarns 10 and 11 alone. On the other hand if single feed plain fabric is preferred in the leg and instep, this may be had by retracting either the feed 40 or the feed 41 together with the elastic yarn feed 42 as will be readily understood.

My invention is not to be considered as limited to the use of a machine having but two inelastic yarns and two sets of knitting cams since more of such feeds and cams may be provided if desired. In any case, it will be seen that, in the stocking top, the rounds of the elastic yarn will be incorporated in courses spaced by a number corresponding to the number of inelastic yarns employed in the knitting.

As an alternative construction, the knitting of the stocking top may be accomplished, if desired, as in Fig. 7 without retracting cam 35 (as hereinbefore explained) after the formation of the selvage edge. In such case, the top fabric will then be characterized throughout by having elongated loops of the yarn 10 like those designated n' in Fig. 2 connecting alternate courses, and regular loops n^2 of the yarn 11 in alternate wales of intervening courses. The top of the alternative fabric is thus formed throughout as an accordion stitch structure instead of merely having an accordion stitch selvage as in the first described embodiment.

Having thus described my invention, I claim:

1. In a top for a seamless stocking, a starting course of inelastic yarn with regular plain loops in alternate needle wales and elongated plain

loops in intermediate wales; a second course with regular plain loops of another inelastic yarn interknitted with the regular plain loops of the first course and floats of said another inelastic yarn extending behind the elongated plain loops of the first course; a third course like the starting course of the first mentioned yarn with plain regular and plain elongate loops respectively interknitted with corresponding plain regular and plain elongated loops of said starting course; a fourth course like the second course having plain regular loops interknitted with the plain regular loops of the second course, plain elongated loops interknitted with the plain elongated loops of the starting course, and floats passing behind the plain elongated loops of the third course; a fifth course all of regular plain loops of the first mentioned yarn interknitted with the plain elongated loops of the third course and the plain regular loops of the fourth course; following courses all of plain regular loops in which the first inelastic yarn is alternated with the second inelastic yarn; and an elastic yarn extending through all of the sinker wale loops of the starting course and interlaced in alternate courses of the remaining portion of the stocking top.

2. A stocking having an elastic top characterized as in claim 1, and having its leg and instep portions formed by plain regular loops alternately from the two inelastic yarns.

3. The method of producing a top for a seamless stocking which comprises the steps of forming, from an inelastic yarn, a plain course having elongated needle wale loops in alternation with regular needle wale loops over an elastic yarn so that the latter passes through all of the sinker wale loops of said inelastic yarn; forming from a second inelastic yarn, a course in which plain regular needle wale loops are interlooped with the

regular loops of the first inelastic yarn and floating said second yarn behind the plain elongated loops of the first inelastic yarn; forming, from the first inelastic yarn, another course with regular plain loops interlooped with the plain regular loops of the second course and with elongated loops interlooped with the plain elongated loops of the first course and at the same time interlacing the elastic yarn between the elongated loops only of the first and third courses; forming a fourth course like the second course from the second inelastic yarn; forming from the first inelastic yarn, a fifth course all of regular plain loops and interlacing the elastic yarn between the plain elongated loops of the third course and the corresponding plain regular loops of said fifth course; and forming plain courses of regular loops from the inelastic yarns in alternation and interlacing the elastic yarn in alternate courses 20 thereafter to complete the stocking top.

4. The method of producing a stocking by forming a seamless stocking by first forming an elastic top in accordance with claim 3 and thereafter knitting the leg and instep of plain courses 25 with regular loops alternately from the two inelastic yarns, with omission of the elastic yarn.
